DESIGN FOR A FLUORESCENT LAMP FIXTURE

Charles F. MacCarthy, Salem, Mass., assignor to Hygrade Sylvania Corporation, Salem, Mass.,
a corporation of Massachusetts

Application June 11, 1940, Serial No. 92,930

Term of patent 3½ years

To all whom it may concern:

Be it known that I, Charles F. MacCarthy, citizen of the United States, residing at Salem, in the county of Essex and State of Massachusetts, have invented a new, original, and ornamental Design for a Fluorescent Lamp Fixture, of which the following is a specification, reference being had to the accompanying drawing, forming part thereof.

I claim:

The ornamental design for a fluorescent lamp fixture, as shown.

CHARLES F. MACCARTHY.
